TOY BASKETBALL GAME GOAL

Jack L. Breneman, Orchard Park, N.Y., assignor to
The Quaker Oats Company, Chicago, Ill.

Filed Dec. 5, 1973, Ser. No. 421,773

Term of patent 14 years

Int. Cl. D21—01

U.S. Cl. D34—5 VV

FIG. 1

FIG. 2

FIG. 3

FIG. 4

FIG. 5

FIG. 1 is a front perspective view of a toy basketball game goal showing my new design;

FIG. 2 is a rear elevation thereof;

FIG. 3 is a side elevation thereof as viewed from the right in FIG. 1;

FIG. 4 is a top plan view thereof; and

FIG. 5 is a bottom plan view thereof.

I claim:

The ornamental design for a toy basketball game goal, substantially as shown.
